UNITED STATES PATENT OFFICE.

EDWIN CHARLES LARRY, OF ROCHESTER, NEW YORK, ASSIGNEE TO GENERAL RAILWAY SIGNAL COMPANY, OF GATES, NEW YORK, A CORPORATION OF NEW YORK.

CHECK ON LIGHT-SIGNAL LAMPS.

Application filed May 5, 1923, Serial No. 636,997. Renewed April 5, 1927.

This invention relates to railway signaling, and particularly to signaling systems including electrically lighted signals wherein notice is given at a signal point in the rear of a particular signal when danger conditions exist and a lamp in said particular signal is burned out.

In modern railway signaling electric incandescent lamps have to a large extent replaced the old oil lantern for illuminating the roundels of semaphore signals. Also, multiple aspect color light signals and position light signals have to a certain extent replaced semaphore signals both for night and day light signaling. Although the expedient of using electric lamps for railway signaling has many advantages, one disadvantage creeps in by their use, namely, the uncertain and indefinite life of the lamp filament, with the result that it is impossible to determine even roughly when a particular lamp is going to burn out. If the danger lamp burns out, there is nothing but a dark signal under danger traffic conditions to inform the engineer of danger ahead.

With the above and certain other considerations in mind, it is proposed in accordance with the present invention to provide an arrangement of circuits and devices whereby if the lamp of a semaphore signal, or the danger lamp or lamps of a multiple aspect color light or position light signal burn out, the next signal in the rear of such signal will give notice to safeguard the train. More specifically, it is proposed in accordance with the particular invention illustrated to provide a multiple aspect color light signal at the entrance to each block of a railway system, and to provide means whereby if the red lamp of a signal burns out and this signal should be indicating danger at the time, the next signal in the rear thereof will indicate danger and the next signal in the rear thereof will indicate caution. The means provided are such that if a red lamp is extinguished because traffic conditions are either clear or caution and for this reason the red lamp is not lighted, no such indication will be given by the signal in the rear.

Other objects, purposes, and characteristic features of the invention will in part be apparent and in part be pointed out in the following detailed description.

In the drawing has been illustrated a sec-

tion of a railway track including signals automatically operated by track circuits in the usual manner, and in which the signals and their associated relays have been conventionally illustrated.

Referring to the drawing, there has been illustrated a section of automatic signal territory of a signal system as shown by the rails 1 divided by insulating joints 2 into blocks, the block I and the adjacent ends of two other blocks H and J being shown. Since each of the various blocks are substantially the same, like parts have been given the same reference characters with distinctive exponents.

At the entrance of each block has been shown a multiple aspect color light signal S having a red (danger) lamp R, a yellow (caution) lamp Y and a green (clear) lamp G. There are also provided suitable relays at each signal location, a track relay T, a selecting relay SR, and a check relay CR being shown. These relays are of the usual two-element or polarized alternating current type, the track relay T being of the standard form and the selecting relay SR and check relay CR being of a similar type but having slow acting or retarded features. These relays are preferably of the induction type, although dynamometer type relays may be used substantially equally as well. If the source of energy is direct current, suitable polarized direct current relays may be used instead of the relays conventionally shown. The energy for the particular system illustrated is shown transmitted over line wires 3 to a suitable transformer 4 located at each signal location.

Under normal clear traffic conditions with no train in any of the blocks illustrated, the relays T, SR and CR at the entrance of block I are energized and have their respective local windings connected in multiple across the secondary winding of the transformer 6. The secondary transformer 6 has its primary winding supplied by energy from the secondary winding of the transformer 4, as shown. The track relay T is connected to the rails of the block I in the usual manner, the track circuit of the block I having its energy supplied from the transformer 4 of the block J in advance. The circuit for energizing the track winding of the track relay T may be traced as follows: Beginning at the secondary winding of the

transformer 7^1 of the block J, wire 8^1 , the usual series track impedance 9^1 , front contact 10^1 of the check relay CR ^{1} , wire 11^1 , the track rail of the block I, wire 12 , track 5 winding of the track relay T, wire 13 , the other rail of the block I, wire 14^1 , front contact 15^1 of the check relay CR ^{1} , wire 16^1 back to the secondary winding of the transformer 7^1 .

10 This transformer 7^1 has its primary winding energized by the secondary winding of the transformer 4^1 through the following circuit: Beginning at the secondary winding of the transformer 4^1 , wires 18^1 and 19^1 , contact 20^1 operated by the selecting relay SR ^{1} , wires 21^1 , primary winding of the transformer 7^1 , wires 22^1 and 23^1 , front contact 24^1 of the selecting relay SR ^{1} , wires 25^1 and 26^1 back to the secondary winding 20 of the transformer 4^1 .

With the track relay T energized and in its normal condition, as shown, a circuit is completed for the selecting relay SR comprising: The secondary winding of the transformer 6, wires 27, 28 and 29, contact 25 30 of the track relay T, wires 31 and 32, winding of the selecting relay SR, wires 33, 34, 35 and 36 leading to the secondary winding of the transformer 6.

30 With the selecting relay SR in its energized position, as just explained, a circuit for energizing the check relay CR is completed which may be traced as follows: Beginning at the secondary winding of the transformer 6, wires 38 and 39, winding of the check relay CR, wires 40 and 41, resistance 42, wire 43, front contact 44 of the selecting relay SR, wires 45 and 46 back to the secondary winding of the transformer 6.

40 With the track relay T energized to the normal position and with the selecting relay SR energized, a circuit for energizing the green lamp G is completed which comprises the following: Secondary winding of 45 the transformer 6, wires 38, 48 and 49, the green lamp G of the signal S, wire 50, contact 51 of the track relay T, wire 52, front contact 53 of the selecting relay SR, wires 54 and 46 leading back to the secondary winding of the transformer 6.

45 *Change from clear to danger.*—The normal clear traffic conditions of the signals having been described, let us now consider the various operating conditions when a 55 train passes through the blocks H, I and J and then leaves the block J. Assuming that a train is moving from left to right in the normal direction of traffic, as indicated by the arrow. As the train enters the block I, the track relay T is shunted by the wheels and axles of the train which causes the track relay to be deenergized and its contacts 30 and 51 to assume the pendent position. The dropping of the contact 51 of 65 this relay T to its pendent position ex-

tinguishes the green lamp G. The dropping of the contact 30 of the relay T to its pendent position breaks the energizing circuit for the selecting relay SR heretofore traced, thus causing this relay SR to assume its de- 70 energized position and thereby interrupting the energizing (pick-up) circuit for the check relay CR heretofore traced including the resistance 42.

Simultaneously with the interrupting of 75 the energizing circuit for the relay CR just traced, another circuit (stick circuit) is completed for energizing this relay including the main winding of the check relay CR and the red lamp R of the signal S in series, 80 which may be traced as follows: Beginning at the secondary winding of the transformer 6, wires 38 and 39, main winding of the check relay CR, wires 40 and 57, red lamp R of the signal S, wire 58, front contact 59 of the relay CR (this relay not yet having assumed its deenergized position because it is slow acting, and also because it is not deenergized until the relay SR has moved to the deenergized position and 90 dropped the front contact 44), wire 60, contact 53 of the relay SR in its deenergized position, wires 54 and 46 back to the secondary winding of the transformer 6.

It should be especially noted at this time 95 that the circuit just traced, including the main winding of the check relay CR and the danger lamp R of the signal S in series, is a stick circuit, since it includes the front contact 59 of this relay CR. This stick circuit is completed before the armature and movable contacts of the check relay CR assume the deenergized position, this being possible on account of the features of this check relay as heretofore explained.

It will be noted that the red lamp R is energized by a circuit including the winding of the relay CR struck up by a front contact of this same relay, so that if the filament of the red lamp R burns out, or 100 this circuit is momentarily opened due to an intermittent break in the circuit, the relay CR will assume its deenergized position, thereby disconnecting the track circuit of the block H from the track transformer 115 7, thus causing the signal at the rear of the block I to assume the danger position in a manner similar to what it would if the block H were occupied by a train. This stick contact 59 may be omitted altogether, if desired, but is preferably provided so that an intermittent opening and closing of the stick circuit or an open circuit in the red lamp followed by a short circuit around the lamp will cause permanent deenergization 120 of the check relay.

125 *Change from danger to caution.*—Assuming now that the train in question moves out of the block I into the block J. As the train enters the block J, the track relay T ^{1} and the 130

selecting relay SR^1 are deenergized in the same manner as were the track relays T and SR at the entrance of the block I when the train entered this block. Similarly, the check relay CR^1 will remain energized through a stick circuit including the red lamp R of the signal S^1 . It will be noted that with the relay SR^1 in its deenergized position, the contacts 20^1 and 24^1 will assume their lowermost position and by so doing will reverse the relative instantaneous polarity of the transformer T^1 with respect to the instantaneous polarity on the transmission line 3. It is evident that if the instantaneous polarity of this transformer is reversed that the relative polarity of the current flowing in the track circuit of the block I is reversed, and therefore as soon as the rear end of the train in question passes out of the block I the relay T will assume its reverse energized position, that is, will be energized so that the contacts 51 and 30 assume the dotted position shown in the drawing.

With the track relay T in the reverse position, the selecting relay SR is again energized the same as under normal clear conditions, thereby again energizing the check relay CR through the pick-up circuit including the resistance 42 . With the contact 51 of the track relay T in the dotted position, a circuit for the yellow lamp is completed which includes the same parts as the circuit for the green lamp, except that wire 61 , caution lamp Y and wire 62 have been substituted for the wires 50 , green lamp G and wire 49 .

Change from caution to clear.—As the train in question moves out of the block J , the track relay T^1 is again energized but in the reverse direction, so that its contacts assume the dotted position. This change of traffic conditions again energizes the relay SR^1 , thereby again reversing the relative polarity of the track circuit of the block I back to its original or normal condition, which in turn causes the track relay T at the entrance to the block I to assume its normal position, as shown in the drawing, thereby again energizing the green lamp G and extinguishing the yellow lamp Y . When the track relay T moves from the reverse position to the normal position, as just explained, the energizing circuit for the selecting relay SR is momentarily open. This does not, however, allow the relay to assume its deenergized position, by reason of the slow acting characteristics of this relay. If desired, the front contact 44 and back contact 53 may be so adjusted that either one or the other of these contacts are always closed. If this is done, the relay CR need not have the slow acting characteristics, for the reason that the pick-up circuit including resistance 42 is not broken until the stick circuit is completed.

Failure or red lamp when signal should indicate danger.—Let us now assume that the block J is occupied by a train which causes the track relay T^1 to assume the deenergized position, thereby deenergizing the selecting relay SR^1 which will momentarily cut current off of the check relay CR^1 , but on account of the slow acting features of the relay CR^1 causes this relay CR^1 to be maintained energized through a stick circuit, as heretofore explained. Similarly, the reversal of the relative polarity of the track circuit of the block I causes the signal S at the entrance of the block I to indicate caution, for reasons heretofore made clear.

If now the red lamp R of the signal S^1 which is lighted, as just explained, burns out, the check relay CR^1 is deenergized because its energizing circuit including the red lamp R is broken, thus dropping its back contacts 10^1 and 15^1 and completely cutting energy off of the track circuit of the block I . This, of course, causes the signal S at the entrance to the block I to indicate danger, and the signal next in the rear thereof to indicate caution for reasons apparent from the foregoing description. The resistance 42 which at times is included in series with the relay CR may be substantially equal to the resistance of the red lamp R , so that the energizing current for the relay CR , whether flowing through the red lamp R or through the resistance 42 , is substantially the same. If desired, however, this resistance may be less than that of the red lamp for the reason that less current is ordinarily required to hold up a relay (specially if a tractive type relay is used) than is necessary to pick up the same relay.

It is thus noted that a signaling system has been devised which will indicate red or danger in the rear of an occupied block, or a block in danger due to some other cause, regardless of whether the red lamp to the entrance of such block is intact. If the red lamp to the entrance of the immediate block in danger is not lighted because its circuit is not intact for some reason or other, the next signal in the rear will have its red lamp lighted and the next succeeding signal will indicate caution. Similarly, if the red lamps of two successive signals should be burned out and the block of the first of said signals is occupied, the second signal in the rear of such signal will indicate danger and the third signal in the rear thereof will indicate caution, and so on, so that in any event there will be at least one caution signal followed by a danger signal to the approach of a danger traffic condition.

Although the present invention has been illustrated only in connection with multiple aspect color light signals, obviously the same general arrangement may be applied to position light signals. Also, where sema-

phore signals are illuminated electrically the same general arrangement may be provided only that in this event the selecting relay SR may be omitted. This is because 5 there is only one lamp used in semaphore signals and no selection is required. This lamp may be connected directly in series with a check relay, such as the relay CR, whereby if this lamp burns out the track 10 circuit of the block next in the rear will be deprived of its energy, and will cause the signal in the rear to indicate danger. If desired, the check relay may in this event be energized independently by a signal circuit 15 controller when the signal is in the clear or caution position, so that the next signal in the rear will only indicate danger under danger traffic conditions of the signal ahead.

Having thus shown and described only 20 one specific embodiment of the invention, it is desired to be understood that various modifications and changes may be made to adapt the invention to the various types of systems ordinarily employed in practice, 25 without departing from the scope of the invention or the idea of means underlying the same.

What is desired to be secured by Letters Patent of the United States, is:—

30 1. In a railway signaling system, the combination with a trackway divided into blocks, of a signal at the entrance to each block, automatic means for operating said signals in accordance with traffic conditions 35 including the usual track circuit and associated track relay, and means effective under danger traffic conditions of a certain block for causing the signal at the entrance to the next block in the rear to indicate 40 danger when the lamp for illuminating the signal at the entrance to said first mentioned block under danger traffic conditions is extinguished.

2. A railway signaling system comprising, 45 a trackway divided into blocks, an automatically operated signal at the entrance to each block, and means for causing the first signal which has its danger lamp circuit intact in the rear of a certain block to 50 indicate danger under danger traffic conditions of said certain block in case of failure of a lamp of the signal at the entrance to said certain block.

3. A railway signaling system comprising, 55 a trackway divided into blocks in the usual manner, a track circuit for each block including a track relay, a signal including a danger lamp at the entrance to each block controlled by the corresponding track relay, and means for deenergizing the track 60 circuit of a block when the next block in advance is in danger and the lamp for giving the danger indication at the entrance to said block in advance is extinguished.

65 4. A light signaling system comprising,

a light signal including a clear, a caution, and a danger lamp, a relay, means for energizing said relay under clear and caution traffic conditions irrespective of the flow of current through the clear or caution lamps, 70 and means for connecting said relay in series with said danger lamp under danger traffic conditions, whereby the energizing of said relay under danger traffic conditions is dependent upon the flow of current 75 through the danger lamp.

5. A light signaling system comprising, a light signal including a clear, a caution, and a danger lamp, a relay, means for energizing said relay under clear and caution traffic conditions irrespective of the integrity of the circuits through said clear and caution lamps, and means for connecting said relay in series with said danger lamp under danger traffic conditions, said last mentioned 80 means including a contact of said relay closed only if the relay is energized.

6. A railway signaling system comprising, a trackway divided into blocks, a light signal at the entrance to each block having a 90 danger lamp, a check relay, means for automatically connecting said check relay in series with said danger lamp if the corresponding block is occupied, traffic detecting means, a normally closed circuit including said traffic detecting means which is interrupted upon the de-energization of said check relay, and means for energizing said check relay independently of the flow of current through 95 said danger lamp if the corresponding block is not occupied.

7. In a light signal system; the combination with signals each comprising a clear, a caution and a danger lamp, and located at a plurality of points along the track; a check relay for each signal; two energizing circuits for said check relay; one circuit including a danger lamp of the corresponding signal and the other a resistance equivalent to that of the danger lamp; a selecting relay for alternately closing said circuits; and means for controlling the next signal in the rear by said check relay.

8. A railway signaling system comprising, 115 a track divided into blocks, a signal having lamps and adapted to indicate clear, caution, or danger and located near the entrance to each block, a check relay at each signal automatically connected in series with the danger lamp of said signal under danger indicating conditions of said signal, and means for controlling the next signal in the rear by said check relay.

9. In an automatic block signalling system for railroads, a track divided into blocks, a color light signal including a danger lamp associated with each block, and means associated with each signal for energizing the danger lamp of a given block when danger traffic conditions exist in the first block in 120 125 130

advance thereof and the danger lamp of said advance block is deenergized.

10. In a color light automatic block signalling system for railroads, in combination with a light signal at the entrance of each block including a lamp for giving a stop indication when lighted, a relay at each signal controlling the indication of the signal next in the rear and causing it to give a stop indication if said relay is deenergized, and automatic means for rendering the energization of the relay of each signal dependent upon the flow of current through said lamp of the corresponding signal upon the entrance of a train into the corresponding block.

11. In a color light automatic block signalling system for railroads, a track divided into blocks having track circuits, a signal associated with each block and including a danger lamp, a relay at each signal acting when de-energized to interrupt the flow of track circuit current in the block in the rear, a circuit including said danger lamp for energizing said relay under dangerous traffic conditions, and means for maintaining the flow of track circuit current to the block in the rear under clear or caution traffic condition independently of said circuit and of the flow of current through said danger lamp.

30. 12. In a signaling system, the combination with a railway track divided into blocks by insulating joints each including the usual closed track circuit and a track relay, a multiple aspect signal at the entrance to each block controlled by the track circuit of said block and a track circuit of the next block in advance, a stick relay having a pick-up circuit and a stick circuit associated with each signal which stick relay when in its de-energized condition opens the track circuit of the next block in the rear, and means for alternately closing said pick-up and said stick circuits upon the passage of each train.

13. In a signaling system, the combination with a railway track divided into blocks by insulating joints each including the usual closed track circuit and a track relay, a multiple aspect signal at the entrance to each block controlled by the track circuit of said block and a track circuit of the next block in advance, a check relay having two energizing circuits associated with each signal which check relay when in its de-energized condition opens the track circuit of the next block in the rear, and means for closing one of the circuits of said check relay under favorable traffic conditions and for closing the other circuit of said check relay under unfavorable traffic conditions.

60. 14. In a signalling system; the combination with a railway track divided into blocks by insulating joints each including the usual closed track circuit and a track relay; a multiple aspect color light signal including a clear, a caution and a danger lamp located at

the entrance to each block and controlled by the track circuit of said block and the track circuit of the next block in advance; a check relay having two energizing circuits associated with each signal which check relay when in its de-energized condition opens the track circuit of the next block in the rear; and means for closing one of the circuits of said check relay under favorable traffic conditions, and for closing the other circuit of said check relay under unfavorable traffic conditions; the circuit of said check relay closed under unfavorable traffic conditions including a danger signal lamp.

15. In a block signal system for railroads, a track divided into blocks each provided with a track circuit, a slow release relay for each block having pole-changing contacts controlling the track circuit of the first block to the rear and governed by the track circuit of the corresponding block, a signal at the entrance to each block capable of giving three distinctive indications, and means for controlling each signal from the track circuit of the corresponding block and the pole-changing contacts of the slow release relay of the next block in advance.

16. In a block signal system for railroads having tracks divided into blocks each provided with a polarized circuit and track relay, a slow release relay for each block having an energizing circuit through a front contact of the track relay of a corresponding block, pole-changing contacts operated by each slow release relay for governing the relative polarity of track circuit current supplied to the block next in the rear, and a multiple indication signal at the entrance to each block governed by the track relay and slow release relay of that block.

17. A block signal system comprising polarized track circuits for the blocks, a slow release relay for each block automatically de-energized whenever that block is occupied, and pole-changing contacts shifted by said relay as it is energized and de-energized for governing the relative polarity of current supplied to the track circuit next in the rear.

18. In a block signal system, a multiple indication light signal at the entrance to each block having three control circuits for giving distinctive indications, a control relay responsive to the relative polarity of current supplied thereto as well as the absence of current, a slow release relay de-energized when said control relay is de-energized and having pole changing contacts for governing the track circuit of the first block to the rear, two of said control circuits including the contacts selectively closed by operation of said control relay in response to different polarities of current supplied thereto, the third control circuit

including the contacts closed when said slow release relay is de-energized.

19. An automatic block signal system for railways having polarized track circuits and three indication color light signals, comprising a polarized control relay for each signal de-energized when the corresponding block is occupied and energized with opposite relative polarities dependent on whether the next block in advance is occupied or unoccupied, a slow release relay governed by each control relay and de-energized if its control relay is de-energized, pole-changing contacts operated by each slow release relay for determining the relative polarity of current supplied to the control relay next in the rear, a danger control circuit for each light signal including a back contact of the corresponding slow release relay, and clear and caution control circuits for each signal selectively governed by contacts of the corresponding control relay selectively closed accordingly as said relay is energized with one or the other polarity.

20. In a signal system for railroads, two light signals, a circuit for one light signal including the winding of a check relay completed under a first predetermined traffic condition ahead, a circuit for the other light signal completed under a second predetermined traffic condition ahead, and means for energizing the said other light signal under said first predetermined traffic condition ahead, when a check relay is de-energized.

21. A railway signalling system comprising, a trackway divided into blocks, an automatically operated signal at the entrance to each block, and means for causing the first signal which has its danger lamp intact in the rear of a certain block to indicate danger under danger traffic conditions of said certain block in case of failure of the circuit of the danger lamp of the signal at the entrance to said certain block.

In testimony whereof I hereby affix my signature.

E. CHARLES LARRY.
